[57] CLAIM

The ornamental design for a truck mounted crane, as
shown and described.

DESCRIPTION

FIG. 1 is a side elevational view of a truck mounted
crane showing my new design, the opposite side being
substantially a mirror image thereof.

FIG. 2 is a top plan view thereof.

FIG. 3 is a bottom plan view thereof.

FIG. 4 is a front elevational view thereof.

FIG. 5 is a rear elevational view thereof.

The broken lines in the drawing are for illustrative
purposes only.

FIG. 1
